CLAIM

The ornamental design for a collapsible box, as shown and described.

DESCRIPTION

FIG. 1 is a top plan view showing my new design for a collapsible box in an unfolded, flat state, and the lines shown in dashed lines are fold lines,

FIG. 2 is a front and left side perspective view thereof, in a partially folded position and the lines shown in dashed lines are fold lines,

FIG. 3 is a top, sides and rear perspective view thereof, the lines shown in dashed lines are fold lines,

FIG. 4 is a right side and rear perspective view thereof; and, FIG. 5 is a bottom view thereof, the lines shown in dashed lines are fold lines.

The dashed lines in the drawings depict fold lines and form part of the claimed design.
